UNITED STATES PATENT OFFICE.

ALBERT D. BINGHAM, OF NEW HAVEN, CONNECTICUT, ASSIGNOR TO THE NEW HAVEN WATCH COMPANY, OF SAME PLACE.

WATCH.

SPECIFICATION forming part of Letters Patent No. 340,854, dated April 27, 1886.

Application filed February 3, 1885. Serial No. 154,840. (No model.)

To all whom it may concern:

Be it known that I, ALBERT D. BINGHAM, of New Haven, in the county of New Haven, and in the State of Connecticut, have invented certain new and useful Improvements in Watches; and I do hereby declare that the following is a full, clear, and exact description thereof, reference being had to the accompanying drawings, in which—

10 Figure 1 is a perspective view of my movement from the front, the dial being removed. Fig. 2 is a like view of the same with the dial-wheels, hand-setting mechanism, and front plate removed. Fig. 3 is a perspective view 15 of said movement with the balance-wheel and minutes-wheel removed. Fig. 4 is a plan view of the same with all of the train except the first and second wheels, the escape-wheel, and the lever removed. Figs. 5 and 6 are like 20 views of the hand-setting mechanism, and show, respectively, the same out of and in engagement with the dial-wheels. Fig. 7 is a perspective view of the parts of said mechanism except the wheels separated from each other. 25 Fig. 8 is a perspective view of the spring-barrel from the rear, a portion of the back plate being broken away to show the spring and the winding mechanism. Fig. 9 is a like view of 30 said parts separated from each other. Fig. 10 is a plan view of the same from the rear side, the back plate being removed and portions of the outer ring broken away to show the arrangement of the springs; and Fig. 11 is an enlarged central section upon line $x-x$ of 35 Fig. 8.

Letters of like name and kind refer to like parts in each of the figures.

The design of my invention is, mainly, to increase the running time of a watch-movement 40 without increasing its bulk or lessening its time-keeping qualities; to which end said invention consists, principally, in the relative arrangement of the parts of the time-train, substantially as and for the purpose herein- 45 after specified.

It consists, further, in the relative proportions of the operative parts of the time-train, substantially as and for the purpose herein- after shown.

50 It consists, further, in the location of the

mainspring and the means employed for enclosing the same, substantially as and for the purpose hereinafter set forth.

It consists, further, in the means employed for winding the mainspring, substantially as 55 and for the purpose hereinafter shown and described.

It consists, further, in the means employed for holding the mainspring in position when wound, substantially as hereinafter specified. 60

It consists, further, in the means employed for setting the hands, substantially as and for the purpose hereinafter shown.

It consists, further, in the means employed for throwing the hand-setting mechanism into 65 and out of gear with the dial-wheels, substantially as and for the purpose hereinafter set forth.

It consists, finally, in the means employed for holding the hand-setting mechanism in and 70 out of engagement with the dial-wheels, substantially as and for the purpose hereinafter shown and described.

In the annexed drawings, A represents the 75 back plate, and B the front plate, of my movement, which plates are connected together and held in relative positions by means of pillars C, in the usual manner.

Within the center of the back plate, A, is journaled one end of a mainspring arbor, D, 80 which end projects through said plate sufficiently to enable it to receive a wheel, E, that is secured thereon in any usual way, and has forty-eight teeth. Journaled between the plates A and B at one side of the wheel E is an arbor, 85 F, that is provided with a sixteen-leaf pinion, f, which meshes with said wheel, while above said pinion a wheel, f', that has fifty-four teeth is secured to said arbor, and meshes with a sixteen-leaf pinion, g, that is attached to or 90 formed upon an arbor, G. Said arbor G is journaled between said plates A and B, and, like said arbor F, carries above its said pinion a wheel, g', that has seventy-five teeth.

Extending across the wheel E is a bridge, 95 H, within which and within the plate B, at the center of the latter, is journaled an arbor, I, that carries upon its inner end a twelve-leaf pinion, i, and between the same and the inner face of said plate a wheel, i', having eighty 100

teeth. Said pinion meshes with and receives motion from the wheel g' , while said wheel i' meshes with and imparts motion to a ten-leaf pinion, k , which is secured to or formed upon an arbor, K . The arbor K is journaled between the plate B and bridge H , and, in addition to the pinion k , carries a wheel, k' , which has seventy-five teeth, and meshes with and imparts motion to a ten-leaf pinion, l , that forms part of or is attached to an arbor, L , which is journaled between the plate A and said plate B . The arbor L is provided with a wheel, l' , which has eighty teeth, and meshes with an eight-leaf pinion, m , that is secured to or formed upon an arbor, M , which last-named arbor carries an escape-wheel, m' , that is of usual construction, and is engaged by the pallets n of a lever, N , while said lever is in turn engaged by the roller-pin of a balance-wheel arbor, O .

The rear end of the mainspring-arbor D is journaled within a flanged cover, P , which fits over and is secured to the periphery of the back plate, A , and, in connection with said plate, forms a barrel for a mainspring, Q . A collet, d , secured to or formed upon said arbor between said plate and cover receives the inner end of said mainspring, while the outer end of the latter is attached by a stud, r , in any usual manner, to or upon the inner face of a ring, R , which has substantially the same width as said spring, and is provided upon its periphery with ratchet-teeth r' .

The ring R is provided upon one side with an axially-projecting annular flange, r^2 , which fits into the interior of a radially inward-projecting flange, s , that is provided around the interior at one edge of a second larger ring, S , by which means said ring R is adapted to be rotated within said ring S , while maintaining a position concentric therewith.

The ring S is provided around its periphery with spur-teeth s' , and has such diameter as to enable it to fit closely within the barrel, while free to be rotated therein, for which purpose a spur-pinion, t , is placed within a recess, a , in the plate A , in position to mesh with said teeth s' and to receive the end of a stem-arbor, T .

The inner ring, R , is intended to rotate only in the direction necessary to wind the mainspring Q , and is engaged by a spring-pawl, U , which is secured at one end to the plate A , and has its free end in contact with the toothed periphery of said ring. A lug, u , projects from the engaging end of said pawl forward through a slot, a' , in said plate A , and furnishes a means whereby said pawl may be released from engagement with said spring whenever it is desired to let down said mainspring.

The ring S is intended to rotate in either direction around the ring R , and in order that such motion may be caused to turn the latter so as to wind the mainspring a spring-pawl, s^2 , is attached to the inner face of said outer ring in position to engage with the toothed periphery of said inner ring. While said ring

S is moving backward its pawl s^2 will trip and pass over the teeth r , but when moved forward will engage with said teeth and cause said ring R to move in the same direction. As thus arranged, a reciprocating motion in opposite directions, or a continuous motion in a forward direction, of said outer ring, S , will cause said inner ring, R , to be turned in the direction necessary for winding said mainspring.

The arbor I extends through the plate B , and upon its projecting portion receives a cannon-pinion, V , which carries a minutes-hand, v , and has journaled upon its barrel a second cannon-pinion, W , that carries an hours-hand, w . Said pinions are connected together by a spur-wheel, X , and pinion x , and, in connection with the latter, constitute dial-wheels of usual construction and arrangement. The arbor L is also extended through said plate B , and upon its projecting end receives a seconds-hand, l^2 . The train thus arranged is so proportioned as to cause the minutes-arbor I and seconds-arbor L to have the required time of rotation, while the relative velocities of said arbors and the spring-wheel arbor D cause said train to run for eight days with one winding of the mainspring, such increased time being secured by the relative proportion and arrangement of parts and without increase in the size of the movement.

In order that the hands may be set when necessary, the following mechanism is employed, viz: Pivoted near one end upon the plate B , beneath the dial A' , is a yoke, B' , which has the form shown in Fig. 7, and is adapted to be moved within certain limits, so as to swing its outer end toward or from the dial-wheel X . A spring, C , attached at one end to said plate B , and having its opposite end in engagement with the short end of said yoke, operates to hold the said outer end of the latter, with a yielding pressure at the limit of its motion, away from said dial-wheel, while a cam-bar, D' , that is pivoted near its center upon said plate B , with its outer end projecting beyond the periphery of the latter, and its inner cam-shaped end, d' , bearing against the inner short end of said yoke, enables said yoke to be turned to the opposite limit of its motion, for which purpose said bar is turned from the position shown in Fig. 5 to the position shown in Fig. 6, by which movement the inner end of said bar carries the short end of said yoke in the same direction until the longitudinal axis of the former is in a line with the pivotal bearing of the latter, as shown, when said parts are automatically held in relative position. To restore said yoke to its normal position, said bar is swung in the opposite direction until out of line with the said pivotal bearing of the former, after which said spring C operates to complete the movement.

Within a recess, b , which is formed upon a circular line within the long arm of the yoke B' , and has an open side adjacent to the dial-wheel X , is a spur-wheel, E' , which loosely fills

said recess and is capable of being rotated therein. A larger spur-wheel, F', journaled upon the short arm of said yoke, meshes with said wheel E' and enables the latter to be rotated within its bearing, and when said wheel E' is thrown into engagement with said dial-wheel by the inward movement of said yoke enables the dial-wheels to be rotated so as to set the hands.

10 The wheel F' has such diameter as to cause its edge to project from beneath the dial when the intermediate wheel, E', is in engagement with the dial-wheel X, as seen in Fig. 6, in which position said wheel F' may be readily 15 rotated with the finger; but when said wheel E' is thrown out of engagement with said wheel X said finger-wheel F' is withdrawn entirely beneath said dial, and can neither be seen nor moved. The bar D' and finger-wheel F' may 20 be wholly within the line of the bezel G', if desired, in which event it will be necessary to open said bezel before setting the hands.

In order that the watch may be regulated without difficulty and a long regulator-arm 25 may be employed, I arrange the hair-spring o upon the dial side of the balance O and extend the regulator o' outward beneath the dial, its outer end being over the case-center H' at a point which is covered by the bezel G' when 30 the latter is closed. Beneath said regulator graduation-marks h' are cut within said center and operate as when formed upon the movement-plate, as has heretofore been the custom.

Having thus described my invention, what 35 I claim is—

1. As an improvement in watch-movements, a time-train in which the first and fourth arbors are journaled at the center of the movement-plates, and the second, the third, the fifth, 40 and the sixth arbors and the escape-wheel arbor are journaled around said center, substantially as and for the purpose specified.

2. As an improvement in watch-movements, a time-train which is composed in part of a 45 main or first arbor, an escape-wheel arbor, and five intermediate arbors, with their wheels and pinions, and said first arbor and the fourth arbor are journaled at the center of the movement, and the remaining arbors, with 50 the escapement, are arranged around the same, substantially as and for the purpose shown.

3. As an improvement in watch-movements, a time-train which is composed of a first arbor that carries a wheel having forty-eight teeth, 55 a second arbor which has a sixteen-leaf pinion and a wheel with fifty-four teeth, a third arbor having a sixteen-leaf pinion and a wheel that has seventy-five teeth, a fourth arbor which is provided with a twelve-leaf pinion 60 and a wheel with eighty teeth, a fifth arbor that has a ten-leaf pinion and a wheel with seventy-five teeth, a sixth arbor which has a ten-leaf pinion and a wheel with eighty teeth, and an arbor that is provided with an eight- 65 leaf pinion and carries an escape-wheel having fifteen teeth, said parts being combined substantially as and for the purpose set forth.

4. A watch-movement in which the main-spring is located in rear of the time-train, and is contained within a recess that is formed 70 by and between the rear movement-plate, and a covering-disk which at its edge embraces and is secured to the periphery of said plate, substantially as and for the purpose shown and described.

5. As a means for winding a mainspring, an annular toothed ring adapted to be reciprocated around a spring-containing ring or barrel, in combination with means whereby said outer ring, when thus reciprocated, may 80 be caused to engage with and move said inner ring or barrel upon its forward motion, substantially as and for the purpose shown and described.

6. In combination with the mainspring Q, 85 inclosed between the flanged cover P and back plate, A, and having its inner end attached to the collet d, the ring R, provided with the peripheral ratchet-teeth r, the ring S, having the radial flange s and peripheral spur-teeth 90 s', the spring-pawl s' and U, the stem-arbor T, and the spur-wheel t, substantially as and for the purpose specified.

7. In combination with the ring R, inclosing the mainspring Q, and adapted to be rotated around and with the same, the spring-pawl U, arranged to engage with the toothed periphery of said ring, and provided with the arm u, which projects through the slot a in the plate A, substantially as and for the purpose shown.

8. In combination with the dial-wheel X, the yoke B', pivoted near one end upon the plate B, and provided within its long arm with the circular recess b, the spring C', engaging with the short arm of said yoke, the spur-wheel E', placed within said recess b, and the spur-wheel F', pivoted upon the short arm of said yoke, said parts being constructed to operate in the manner and for the purpose 110 substantially as set forth.

9. In combination with the yoke B' and its connecting parts, the bar D', pivoted upon the plate B and provided with the cam end d', which is adapted to impinge upon and move 115 the short arm of said yoke, substantially as and for the purpose shown and described.

10. In combination with the yoke B' and its connecting parts, the spring C', secured to the plate B and engaging with the short arm of 120 said yoke, and the bar D', pivoted upon said plate, and adapted to have its inner end engage with and lock the short arm of said yoke, when the latter is in position to permit the hands to be set, substantially as and for the 125 purpose specified.

In testimony that I claim the foregoing I have hereunto set my hand this 6th day of January, 1885.

ALBERT D. BINGHAM.
